ULRICH BISCHOF, OF HOREN, SWITZERLAND, ASSIGNOR TO GEBR. STÄUBLI & CO.,
OF HOREN, ZURICH, SWITZERLAND.

THREAD-STITCHING MACHINE HAVING A THREAD LAYER WITH TWO POINTS.

Application filed July 21, 1924. Serial No. 727,377.

To all whom it may concern:

Be it known that I, ULRICH BISCHOF, a citizen of the Republic of Switzerland, residing at Horgen, in the Canton of Zurich, Republic of Switzerland, have invented certain new and useful Improvements in Thread-Stitching Machines Having a Thread Layer with Two Points, of which the following is a specification.

10 In thread-stitching machines of the type having a thread layer with two points each stitch is tied off by a separate thread and is then drawn tight.

15 In the well-known thread stitching machines of this type the tying off is effected in various ways. In such machines the thread layer used for this purpose is provided with two points lying one behind the other in the direction of motion of the thread layer, which are so arranged that the point, which catches the tying off loop, lies in front of the first sewing-needle, when the thread layer is in its initial position. It is obvious, that for stitching with such an arrangement the needles must be placed relatively far apart and that consequently books, which, after being stitched, are cut into two to six separate books, the length of the back of which is only a few centimeters in length (waistcoat pocket size), cannot be bound on machines of this kind, as the position of the stitches should in such small books be correspondingly close together. In addition to this the needles and the thread layers frequently break, as the sewing-needle at the commencement of the stitching operation must move down between the two points of the thread layer and, even when there is only a slight amount of play or bending in the members for making the stitches, there is a danger of the needle striking against one of the points.

20 In other known types of thread-stitching machines the thread layer performs a small turning movement about its longitudinal axis in addition to the longitudinal motion for the purpose of catching the loop in the thread, in which case there is the danger that, during the turning movement of the thread layer, the point of the same may not catch the loop. For making this turning movement of the thread layer possible an opening is provided in the table, for giving

the thread layer the necessary clearance for 55 this movement.

According to the present invention the two points of the thread layer are located one above the other and the eye of the sewing-needle forming the tying off loop 60 lies lower than the eye of the first needle, while the point of the thread-layer, which catches the tying off loop, passes below the eye of the first needle, when the loop of the stitch is formed by the other point. 65 By this arrangement books, the length of the back of which is only a few centimeters, may be bound on the machine, since, as will be described below, the distance between the two adjacent needles need only be slightly 70 greater than the width of the thread layer itself. In the accompanying drawing three constructional examples of the invention are illustrated, in which—

75 Fig. 1 shows the thread layer of the first example in front elevation, side elevation and plan view,

80 Figs. 2-6 show various stages of the stitching operation as performed with the mechanism according to the first example, with 80 the thread-layer in various positions,

85 Figs. 7-8 each show a machine with two thread layers (second and third example) and

90 Figs. 9-10 show the stitches made with 85 the last two machines.

1 is the thread layer with the two points 2 and 3 lying one above the other, 4 is the table, 5 the sheets to be bound, 6 the first needle, 7 the second needle and 8 the hooked 90 needle.

95 Before the commencement of the sewing operation the thread layer occupies the position shown in Fig. 2.

100 On the sheets 5 coming under the needles, the latter pierce the fold (Fig. 2) and thereupon move back again a short distance in a known manner for forming the loop. The thread layer is thereupon moved to the left (Fig. 3) and the upper point 2 of the same 105 enters the loop in the thread formed during the said return motion of the needle 6, while the lower point 3 passes below the eye and the loop of the needle 6 which lies higher than the eye of the needle 7. On the thread layer continuing its forward motion, the loop, which has been caught by the point 2, 110 is drawn out, whereupon both points enter

the loop 9 formed during the piercing and return motion of the needle 7 (Fig. 5) or the loop carried by the point 2 is drawn through the tying up loop drawn out by the point 3, which is in advance, and is thus embraced by the said latter loop. During the continued motion of the thread layer both loops are drawn out beyond the hooked needle 8 (Fig. 6), whereupon by a slight turning motion of the thread layer perpendicularly to the plane of the drawing towards the observer, that part of the thread of the stitch loop lying in front of the thread layer is carried towards the hooked needle and placed over the hook of the same. On the needles rising the loop forming the stitch, which is held by the point 2, is drawn in a known manner through the back of the book to the outside, while the loop held by the point 3 embraces the other loop inside the sheet. The thread layer thereupon returns into the position shown in Fig. 2, whereupon the thread-tightening device (not shown) gradually draws up the threads, which are released, on the return motion of the thread layer taking place, and finally pulls the stitch tight, whereby the tying up loop, which is also released by the thread layer, is also drawn tight.

In Figs. 1-6 it is assumed, that the machine has only one thread layer.

In Figs. 7-8 it is assumed, that each machine has two thread layers. According to Fig. 7 the thread layers, when in the position corresponding to that of Fig. 6 are between two groups of needles, while according to Fig. 8 the thread layers are each on the same side (to the right in the drawing) next to the corresponding group of needles. In the example shown in Fig. 7 the thread layers move in opposite directions during the stitching operation and in the example shown in Fig. 8 in the same direction. In both cases the position of the parts shown in the drawing corresponds to that shown in Fig. 6 and the sheets after being stitched, are cut apart by hand or by mechanical means between the two groups of stitches.

Fig. 7 shows a constructional example

with thread layers working to the right and left and with the needles in the corresponding positions.

As will be seen from Fig. 8 the minimum distance A between two groups of stitches for a book, which is absolutely necessary for the operation of the thread layer is only slightly greater than the breadth of the thread layer, whereby it is possible to place the stitches close together as required in the case of small books, so that 2-6 books, the length of which is only small, can be sewn in one piece on the machine and be subsequently cut apart to form separate books.

As already stated, in the constructional examples shown, the point 3, which catches the tying off loop, can pass clear under the eye of the first needle, as the said eye is placed somewhat higher to correspond to the amount by which one point on the looper is higher than the other point.

Fig. 9 shows the finished sewing corresponding to the constructional examples shown in Fig. 7, and Fig. 10 that corresponding to the constructional form shown in Fig. 8, both of which will be understood from what has been stated above.

Instead of two thread layers being provided in each machine, as shown in Figs. 7 and 8, a greater number of thread layers might be provided.

What I claim is:—

In a thread stitching machine, the combination with eyed sewing needles and a hooked needle, of a thread layer with two points one of which lies above the other, the eye of one of the sewing needles being adapted to form the tying off loop and being lower than the eye of the other needle, and one of the points of the thread layer being adapted to catch the tying off loop and to pass under the eye of the first needle, when the loop of the stitch is formed.

In testimony whereof, I have affixed my signature in presence of two witnesses.

ULRICH BISCHOF.
